UNITED STATES PATENT OFFICE

2,402,444

CONTROL CIRCUIT

Waldemar J. Poch, Moorestown, N. J., assignor to
 Radio Corporation of America, a corporation of
 Delaware

Application May 13, 1943, Serial No. 486,788

2 Claims. (Cl. 178—7.2)

1

This invention relates to television circuits and is directed particularly to a circuit combination whereby the level of the resultant output video signal is suitably controlled.

As was mentioned in a concurrently filed patent application of the same applicant and entitled "Automatic volume control circuits," which application is identified as Serial No. 486,789, it is desirable that the signal level of the television output signal be suitably controlled and its level substantially constant. In television systems wherein the video signals are developed from a scanning action by a cathode ray tube of the so-called "storage type," it frequently happens that the signal energy produced during non-scanning periods of the television cycle cannot efficiently be used to provide the automatic volume control energy because if there is to be a true automatic volume control system, it is desirable that the control effect be produced only by virtue of the useful video or picture signals. To meet such conditions, the present invention provides a circuit arrangement whereby provisions are made for establishing an automatic volume control which is operating only during the periods when the video signal energy is being radiated, and at other times is keyed to an inoperative state.

Various types of scanning systems have been described in the prior art which utilize a so-called "storage type" cathode ray tube to convert the optical image of the scene to be transmitted into video signal energy. Among the types of scanning tubes for such purposes are those that have become known in the art as the "Iconoscope" and the "Orthicon." Each of these types of tubes has been described in the literature fully by all of Zworykin, Iams and Rose, and others, and one of such prior art publications is known as that entitled "The Orthicon, a television pick-up tube" which was described by Messrs. Rose and Iams in the "RCA Review" for October, 1939. Accordingly, no detailed reference to the tube per se will be made herein, except for a broad reference and statement that the image of a scene to be transmitted is focused upon the mosaic electrode element of the scanning tube to produce thereon electrostatic charges of magnitudes proportional to the image brightness at its several elemental areas. The produced charges are then neutralized by a scanning cathode ray beam which scans the camera tube mosaic element under the control of suitable deflecting fields, and, by reason of the charge neutralization, the video or picture signals are produced. These signals are then supplied to external utilization circuits, such as

2

suitable amplifying units, and, when adequately amplified, are supplied to wire or radio communication channels to actuate suitable image reproducing units.

Since the signal energy thus produced is subject to change in level, for various reasons which need not be herein discussed in detail, the present invention has as one of its main objects, that of establishing an automatic volume control unit to provide compensation for signal energy level shifts, which are not due to the character of the transmission itself.

In this application, like in the companion application mentioned, one of the main objects is that of controlling the signal level by an automatic volume control unit which shall not be operative during periods when the usual blanking and sync signals are being transmitted.

Another object of the invention is to provide an automatic volume control unit for television apparatus which is keyed to its operative periods by the presence and absence of the blanking control signals.

A further object of the invention is that of providing a control system of the character described which is effective directly in the amplifier system and, under some conditions, effective to modify the general brightness level of the light image impinging upon the camera tube storage elements so as thereby to vary the output signal level.

Other objects are those of providing improved operation of television systems over that form of operation now generally known and, at the same time, to provide an operating unit in which the fidelity of operation is improved.

The invention is schematically shown in one of its preferred forms by the accompanying drawing, wherein the "Iconoscope" or "Orthicon" type of camera tube is shown in a schematic representation at 11. In the production of output video signalling energy, the optical image of an object, a scene or a subject 13 is projected by way of a lens or optical system 15 and, through a diaphragm or iris 17 (and usually then through another lens element not shown) upon the camera tube housed in the unit 11.

When signal output energy is produced from the camera tube unit 11, it is then supplied to a pre-amplifier unit 19 and a line amplifier unit 21 for amplification purposes. Each of these units 19 and 21 has been described at numerous places in the literature and need not be described herein in more detail except, possibly, to state that each may include one or a plurality of separate

amplifying tubes or stages, as is known. In the case of the line amplifier 21, there would almost always be a plurality of stages of amplification in order that the necessary signal gain may be achieved. The signal output from the line amplifier 21 is then supplied to a further amplifier unit 23, which is generally known as a combining amplifier unit. In this last named amplifier, the blanking and sync signals, which occur at spaced time intervals, such as at the end of each scanning line and at the end of each scanned field of the picture or scene, are mixed with the video signal output of the pre-amplifier 19. The resultant combination of signals is then supplied to a further amplifier tube 25, usually called a "clipper" tube, and controls the current flow therein when supplied to the control electrode element 27.

Signal output energy from the tube 25 is then derived across the cathode resistor 31, which connects between the tube cathode 33 and ground 35. Suitable bias is obtained on the tube by way of the resistor 37 and the bias source 39.

The signal energy which is supplied to the clipper tube 25 is also supplied to a suitable rectifier tube, such as the diode 41, which has its cathode element 43 connected to be energized by the video signals and the plate or anode element 45 connected to ground 35 through the anode resistor 47.

As was disclosed in the companion case hereinafore mentioned, it is desirable that the automatic volume control established by virtue of the rectifier tube 41 shall not be effective during periods of blanking and synchronizing, in order that the control effect provided shall be one functioning only in accordance with the video signal. To this end, the blanking signals are supplied at the terminal 49, as well as to the combining amplifier 23. When the blanking signals are applied at terminal 49, they are impressed in negative polarity (as indicated) so that the anode 45 of the diode will be carried highly negative and a condition of cut-off established in the tube. In this way, the rectifier or diode 41 is keyed to an inoperative state, so to speak, by the blanking signals, and its useful operative period to supply an A. V. C. bias is thus restricted to the periods of video signal transmission.

Under the control of the current passing through the diode 41, a control potential is impressed upon the input electrode of the relay tube 51 through the resistor 52. At the same time, the current flowing in the diode 41 also establishes a bias level upon the clipper tube 25, so that its output may be automatically varied by the control signal. Under the control of the current flow in the relay tube 51, a bias voltage may be impressed upon a selected tube of the line amplifier unit 21 through the resistor 53, assuming the switch arm 55 to be in a position against the upper contact 57, as shown, and bias supplied by a bias source 56. In this way, the output from the amplifier 21 is suitably controlled by way of the bias established upon it from the rectifier or diode element 41.

Under some conditions of operation it may be desirable to establish a control of the video signal production itself. This could occur, for instance, where the output signal reaches an extremely high level due, for instance, to too much light entering the scanning or camera tube and tending to cause saturation effects therein. When such conditions occur, the switch arm 55 may be moved to its lower contact position at 75

contact 59, and a control voltage will then be supplied by way of the conductor 61 (with the control voltage being determined by the energy flow through the diode 41) to vary the current flow through the relay winding 63 and thereby draw the magnetic control element 65, for operating the iris or diaphragm 17, further into the coil, or permits its retraction under the influence of a suitable resilient means (not shown for simplicity of diagram). Various ways and means to control the iris or diaphragm 17 may be provided, including levels, racks and pinions and the like, each of which is well known in the art and thus requires no further illustration than the schematic one shown.

In an alternative form of system, the switch 51 may connect conductor 61 in parallel with the energy supply through resistor 53 to control the line amplifier 21, so that the control effect may become effective both on the iris or diaphragm and the line amplifier unit.

While it has been above suggested that the current flowing in the relay winding 63 is particularly adapted for controlling the opening of the iris or diaphragm 17, it will also be apparent that a somewhat equivalent effect may be achieved by causing a substantial increase in the current in the relay winding to move progressively darker light absorbing filters intermediate the optical system 15 and the opening to the scanning or camera tube 11 through which the light of the optical image enters. Filters of this general type are, per se, generally known and require no specific description. The filters may be arranged on a disc in sector shaped sections and, for varying strengths of current flowing in the relay winding, the filter sections may be moved in stepped manner into the optical path. Alternatively, the filters may be arranged in a strip formation and, by virtue of different current strengths flowing in the relay winding 63, drawn down through the optical path and, with decreases in current, caused to move in the opposite direction under the influence of suitable resilient means, for example. It should be borne in mind, in this connection, that the light enters through a relatively narrow area and, by locating the filter closer adjacent the lens, the desired light gradations on the camera tube may be obtained.

Having now described the invention, what is claimed is:

1. In a television system wherein both video and intermittently present control signals are developed with the control signals occurring for time durations relatively short as compared with the time between successive control signals, means to amplify the video signals, means to combine the amplified video signals and the said control signals, an output amplifier for amplifying the said combined signals, a load circuit connected to receive the amplified combined signals from the output amplifier, a rectifier unit connected to receive also the combined video and control signals from the said combining means and to be rendered operative thereby to draw current to produce a control voltage which is proportional to the average current flowing, means for supplying the produced control voltage from the rectifier to each of the video amplifier and the output amplifier to control the amplification of each, and means to supply the control signals to the rectifier independently of the combined video and control signals to render the said rectifier inoperative to produce control voltages during time

periods coinciding with the presence of the control signals in the combined signal.

2. In a television system wherein both video and control signals are developed with the control signals occurring in spaced time relationship for time durations relatively short as compared with the time between successive control signals, means to amplify the video signals, means to combine the amplified video signals and the said control signals, an output amplifier for amplifying the said combined signals, a load circuit connected to receive the amplified combined signals from the output amplifier, a diode rectifier unit having its anode element connected to receive also the combined video and control signals from the said combining means and its cathode con-

nected to a point of fixed potential, whereby the diode is rendered operative during signal periods to draw current to produce control voltages proportional to the average current flowing, means for supplying the produced control voltage from the diode to each of the video amplifier and the output amplifier to provide an automatic volume control of the amplification of each, and means to supply the control signals to the diode rectifier cathode circuit independently of the supply of the combined video and control signals to key the diode and render the said diode rectifier inoperative to produce control voltages during time periods coinciding with the presence of the control signals in the combined signal.
